United States Patent Office

Des. 221,866
Patented Sept. 14, 1971

221,866

BATTERY CHARGER

Lawrence W. Bonzer, Long Beach, Calif., assignor to
Lear-Siegle, Incorporated, Santa Monica, Calif.

Filed Sept. 30, 1970, Ser. No. 25,264

Term of patent 14 years

Int. Cl. D13—02

U.S. Cl. D26—15

FIG. 1.

FIG. 2.

FIG. 3.

FIG. 5.

FIG. 4.

FIG. 1 is a perspective view of a battery charger showing my new design, such battery charger being shown disposed in an operative position;

FIG. 2 is a top plan view of said battery charger shown in its position of FIG. 1;

FIG. 3 is a perspective view showing said battery charger in a carrying position;

FIG. 4 is a side elevational view of said battery charger shown in its position of FIG. 3; and

FIG. 5 is a side elevational view of the side opposite that shown in FIG. 4.

I claim:

The ornamental design for a battery charger, substantially as shown and described.
